PIPE LOWERING DEVICE

James W. Schuetz, Pittsburgh, Pa., assignor, by mesne assignments, to Blaw-Knox Company, Pittsburgh, Pa., a corporation of Delaware

Application November 4, 1957, Serial No. 694,330

6 Claims. (Cl. 214—1)

This invention relates to devices for lowering pipes, tubes, rods and other elongated objects.

A general object of my invention is to provide improved apparatus for lowering pipes, tubes, rods and other elongated objects. Other objects of my invention are to provide improved apparatus for lowering pipes, tubes, rods and other cylindrical objects which is safe, foolproof and efficient in operation; which positively supports and carries the object being lowered throughout the lowering operation; which utilizes the cylindrical characteristic of the object being lowered to facilitate the handling and lowering thereof; which lowers the objects to be lowered individually; and which is fast and positive in operation and is adapted to lower a relative large number of objects in a short length of time without damage or injury thereto.

Still other objects of my invention include the provision of apparatus for lowering pipes, tubes, rods and other elongated objects which is adapted to align the ends of the objects as the same are lowered; which is strong and rugged in construction and can be economically manufactured and used; and which lowers objects with a minimum forward horizontal displacement. A still further object of my invention is the provision of apparatus for lowering pipes, tubes and the like which is particularly adapted for use in conjunction with modern high speed pipe and tube mills. The manner of attaining these and other objects and advantages of my invention will become apparent from the following description of a preferred embodiment thereof, reference being had to the accompanying drawings in which:

Figure 1 is an elevation of an apparatus embodying a preferred form of my invention with the discharge skids removed;

Figure 2 is a plan view of the apparatus shown in Figure 1;

Figure 3 is an end view of the apparatus shown in Figure 1 together with other apparatus with which it may be associated;

Figures 4, 5, and 6 are schematic elevations of apparatus embodying a preferred form of my invention showing the same in use to lower a pipe; and

Figure 7 is an end view of the apparatus shown in Figure 1, in the position shown schematically in Figure 6.

For convenience I will describe apparatus embodying my invention as a part of a butt-weld mill for lowering the pipe from a first to a second level; it is to be understood, however, that apparatus embodying my invention may be used to lower other types of elongated objects and in environmental surroundings other than the mill herein particularly referred to.

Briefly, apparatus embodying my invention is adapted to lower lengths of pipe from an upper level to a lower level and comprises entry and discharge skids at the upper and lower levels respectively and a plurality of pivotally supported walking beams or arms which have pipe supports at their ends. The beams are adapted to be rocked

2

about their pivotal axes to lift a pipe from the upper or entry skids on the pipe supports at one end of the beams, transfer the pipe to the pipe supports at the other ends of the beams and lower the pipe onto the lower or discharge skids.

Apparatus embodying my invention is indicated generally at Figures 1, 2 and 3 and includes downwardly sloping upper or entry skids E upon which the lengths of pipe P, to be lowered, are received and downwardly sloping lower or discharge skids D upon which the pipes are carried away after they have been lowered. The skids E and D are supported on appropriate framework F and F' respectively and conveniently comprise a plurality of transversely spaced, parallel rails upon which the pipes roll. Stops S at the ends of the respective entry skids E prevent the approaching pipes from rolling off the ends of the skids.

The apparatus 1 also includes a plurality of walking beam units, indicated generally at 2, which are longitudinally spaced and aligned with respect to the longitudinal center line of the pipes P. The number of units 2 necessary in a given apparatus is determined by the length and rigidity of the product to be handled. For convenience I have shown apparatus embodying two such units. Each unit 2 comprises an arm or beam 3 mounted, at its midpoint, on an axis or shaft 4, see Figure 3, and provided at both ends with upper and lower pipe supports 5 and 6, respectively. Shaft 4 is rotatably supported in suitable bearings or pillow blocks 4'.

Pipe supports 5 and 6 are rotatably supported on beams 3 and are tapered so that the pipe sections roll downwardly to end portions or cradles 7 and 8 respectively, see Figures 2 and 3. The upper or entry pipe supports 5 are of sufficient length so that the cradles 7 thereof are disposed forwardly, relative to the stops S of entry skids E by a distance at least as great as the respective radii of the pipe to be lowered so that each pipe supported in the cradles 7 passes in front of stops S without engaging the same when the beams 3 are rotated. Similarly the lower or discharge pipe supports 6 are of greater length than the upper pipe supports 5 and the cradles 8 thereof are forward of the ends of the upper pipe supports 5 by a distance at least as great as the radii of the pipe to be lowered so that each pipe supported in the cradles 8 passes in front of the upper pipe supports 5 without engaging the same when the beams 3 are rotated. A pipe supported in the upper pipe support cradle 7 is engaged by the lower pipe supports when the beams 3 are rotated however.

In order to rotate the beams 3 back and forth in a rocking motion through a limited angle for purposes which will hereinafter more fully appear, I preferably provide bifurcated crank arms 10, which are fixedly secured to the respective axles 4. Preferably, the crank arms are actuated by a motor in the form of a conventional double-acting hydraulic cylinder 12 having a piston rod 13, the motion of which is controlled by suitable hydraulic control means and conduits (not shown). A connecting rod 15 is pivotally connected to the piston rod 13 and to the nearest crank arm 10. Similar connecting rods 16 interconnect each adjacent pair of crank arms 10 so that all of the crank arms are connected in series with each other and with the piston 13. The actuation of the cylinder 12 consequently, simultaneously rotates each beam 3 at the same speed and in the same direction as every other beam in the apparatus. Also, the beams are parallel to each other at all times so that each pipe is maintained level or horizontal while being carried by the pipe supports, and therefore has no tendency to roll endwise off the apparatus. By reversing the direction of movement of piston 13 the direction of rotation of the beams 3 is, of course, reversed; thus,

reciprocation of piston rod 13 rocks the beam 3 through predetermined angles.

The operation of my apparatus is best understood by referring to Figures 4, 5, 6 and 7. Figure 4 shows a pipe P disposed on the entry skids E and against the stops S and the beams 3 positioned so that the upper pipe supports 5 are in contact with the pipe. Movement of the piston rod 13 to the right rotates the beams 3 in a counterclockwise direction thereby raising the pipe supports 5 and lifting the pipe P upwardly above the stops S. Once the pipe P has cleared the tops of the stops S it rolls forwardly under the influence of gravity, down the pipe supports 5 and into the cradles 7 (see Figures 3 and 7). Hydraulic cylinder 12 is then actuated to reverse the direction of the piston rod 13 and move the piston rod and the connecting rods 15 and 16 to the left as viewed. This causes the beams 3 to rotate in a clockwise direction thereby lowering the upper pipe supports 5 and raising the lower pipe supports 6. Since the pipe P is supported forwardly of the stops S at the ends of skids E, it passes downwardly in front of the skids without obstruction until the upper pipe supports are lowered and the lower pipe supports are raised so as to be substantially in the horizontal plane extending through the centers of the shafts 4. In this position the pipe P rests on both the upper pipe supports 5 and the lower pipe supports 6. Continued movement of the piston rod to the left and resulting clockwise rotation of the beams 3 further lowers the upper pipe supports 5 and raises the lower pipe supports 6 so that the pipe is supported by the lower pipe supports 6 alone and is free of engagement with the upper pipe supports, see Figures 6 and 7. The pipe then rolls forwardly under the influence of gravity upon the sloping surface of the lower pipe supports into the cradles 8, which as previously stated are forwardly of the ends 18 (Figure 7) of the upper pipe supports 5 by a distance greater than the radius of the pipe P. The cylinder 12 is then actuated to again reverse the direction of the piston rod 13 and connecting rods 15 and 16, thereby moving them to the right, again rotating the beams 3 in a counterclockwise direction and raising the upper pipe supports and lowering the lower pipe supports. As the beams cross the horizontal center line the pipe passes in front of the upper pipe supports. Continued movement of the piston rod and counterclockwise rotation of the beams 3 brings the pipe downwardly into engagement with the discharge skids D. At the same time the upper pipe supports are moved upwardly into engagement with the next pipe to be lowered. The counterclockwise movement of the beams is continued until the lower pipe supports have been lowered sufficiently to be free of the pipe P, which then rolls forwardly on the downwardly sloping discharge skids D so as to be out of the path of the lower pipe supports. Meanwhile the upper pipe supports have raised the next pipe above the stops S and the cycle is repeated.

In order to obtain the maximum vertical movement of the respective pipe supports during an operational cycle of the apparatus with a minimum angular displacement of beams 3 and longitudinal displacement of piston 13 and connecting rods 15 and 16, I prefer that the beams, crank arms and entry and discharge skids be so disposed that the angular displacement of the beams during each movement thereof is limited to about 65 degrees and that the range be from an angle of about 30° with the vertical, shown, for example, in full lines in Figure 1, to an angle of about 95° with the vertical, shown, for example, in dotted lines in Figure 1. Thus the respective pipe supports do not move through the 30° angle nearest the vertical which, because of the inherent nature of angular motion, causes a minimum vertical movement of the pipe supports. Further, since the upper pipe supports 5 reach their highest position and lower pipe supports 6 reach their lowest position when the beams are at an angle of 30° with the vertical, the upper pipe supports must engage the pipe

on the entry skids and the lower pipe supports must position the pipe to engage the discharge skids when the beams are at an angle with the vertical greater than 30° by an amount such that the additional counterclockwise angular displacement of the beams to an angle of 30° raises the upper pipe supports sufficiently so that a pipe positioned thereon clears the height of the stops S and lowers the lower pipe supports sufficiently so that a pipe positioned thereon clears the ends 19 thereof as it rolls down the discharge skids. Further, the beams 3 must have a maximum angle with the vertical greater than 90° by an amount (preferably about 5°) sufficient so that when the upper pipe supports are in their lowermost position and the lower pipe supports are in their uppermost position the pipe can roll on the lower pipe supports over the ends 18 of the upper pipe supports without engaging same.

The operation of my lowering apparatus advances the pipe longitudinally to the right as viewed, as well as downward. This is because the alternate clockwise and counterclockwise motion of the beams and pipe supports causes the pipe, while being lowered by the respective pipe supports, to be displaced in the same direction during both steps of the lowering process. Accordingly, I preferably provide means to align the ends of the pipe while it is being lowered. Such means conveniently comprises an end stop 20, Figure 1, which is disposed at the right end of the apparatus toward which the pipe is displaced as it is lowered and in transverse alignment with the pipe supports 5 and 6. Thus each pipe section is displaced to the right while being lowered until the end thereof engages the stop and any further tendency to displace the pipe in that direction is prevented by the stop and compensated for by the pipe rolling on the rotatably supported pipe supports which are then carrying the pipe. The stop 20 thus functions to align the adjacent ends of the lengths of pipe as it disposes them in the same vertical plane.

While the apparatus has been described with reference to pipes of round cross-section, it will be appreciated that elongated objects of non-circular cross-section can also be handled if the taper of supports at the ends of the beams is steep enough so that the members will slide into the cradle position at the ends of the beams.

Those skilled in the art will appreciate that various changes and modifications can be made in the preferred form of apparatus described herein without departing from the spirit and scope of the invention. The essential characteristics of the invention are defined in the appended claims.

I claim:

1. Apparatus for lowering pipe, tubes and other objects comprising parallel transversely spaced downwardly sloping entry skids having stops at their respective ends and parallel transversely spaced downwardly sloping discharge skids lower than said entry skids, a plurality of transversely spaced, parallel beams, means rotatably supporting said beams at a level between said entry and discharge skids for rotation in a plane extending transversely thereof about an axis extending parallel therethrough, an upper entry pipe support rotatably supported at one end of each said beam and a lower discharge pipe support rotatably supported at the opposite end of each said beam, said upper and lower pipe supports, respectively, being supported at the corresponding ends of said beams, a bifurcated crank arm fixedly secured to each said beam and adapted to rotate the same, said crank arms being mutually parallel, a hydraulic cylinder having a piston adapted for reciprocal movement therein and adapted to be selectively actuated for movement in a predetermined direction, a connecting rod pivotally secured to and interconnecting said piston and the adjacent said crank arm and a connecting rod pivotally secured to and interconnecting each adjacent pair of said crank arms whereby to connect said piston and

crank arms in series for equal and corresponding motion and an end stop disposed at the end of said apparatus toward which the pipe or objects to be lowered are displaced while being lowered, said pipe supports being sloped inwardly and forwardly, away from said entry skids, to define a cradle for said pipe, said cradle of said upper and lower pipe supports respectively being forwardly, relative to said entry skids, of said entry skid stops and upward pipe supports respectively by a distance at least as great as the radius of the pipe or objects to be lowered.

2. Apparatus for lowering pipe, tubes and other objects comprising downwardly sloping entry skids having stops at their respective ends and downwardly sloping discharge skids at a lower level than said entry skids, a plurality of beams rotatably supported intermediate said entry and discharge skids for rotation in a plane extending transversely and vertically thereof, an upper entry pipe support rotatably supported on each said beam and a lower discharge pipe support rotatably supported at the opposite end of each said beam, said upper and lower pipe supports being respectively supported at the corresponding ends of said beams, a crank arm fixedly secured to each said beam and adapted to rotate the same, a hydraulic cylinder having a piston adapted for reciprocal movement therein and adapted to be selectively actuated for movement in a predetermined direction, and means pivotally secured to said piston and crank arms and connecting said piston and crank arms in series, said pipe supports having sloped lateral surfaces defining a cradle for receiving and supporting the pipe or object to be lowered, said lower pipe supports being of greater length than said upper pipe supports, said cradles of said upper and lower pipe supports respectively being forwardly, relative to said entry skids, of said entry skid stops and said upper pipe supports respectively by a distance at least as great as the radius of the pipe or objects to be lowered.

3. Apparatus for lowering pipe, tubes and other objects comprising entry skids, discharge skids, a plurality of beams rotatably supported intermediate said entry and discharge skids, each said beam rotating about an axis extending through its center and in a plane extending transversely and vertically of said skids, an upper entry pipe support rotatably supported at one end of each said beam and a lower discharge pipe support rotatably supported at the opposite end of each said beam, said upper and lower pipe supports being respectively

supported at the corresponding ends of said beams and being substantially equidistant from the axis of rotation of the respective beams, crank arm means fixedly secured to each said beam and adapted to rotate the same, and 5 means to actuate said crank arm means to rotate said beams in alternating directions through predetermined angles, said pipe supports having sloped lateral surfaces defining a cradle for the pipe or objects to be lowered, said cradles of said upper and lower pipe supports respectively being forwardly, relative to said entry skids, of said entry skids and upper pipe supports, respectively, by a distance at least as great as the radius of the pipe or objects to be lowered.

4. Means for lowering pipes, tubes and other objects 15 from a first position to a second position comprising a longitudinally extending beam having ends and being rotatably supported intermediate its ends on an axis extending transversely of the object to be lowered intermediate said first and second positions, means for oscillating said beam through a predetermined angle, upper object support means carried at one end of said beam and lower object support means carried at the other end of said beam, said upper and lower support means having cradles for receiving and holding the objects to be lowered, 20 said cradle of said upper support means being opposite and in laterally overlapping relationship with said lower object support means and said cradle of said lower support means being disposed forwardly of said upper support means whereby an object held in said upper support means cradle is engaged by and transferred to said lower object support means when said beam is rotated in one direction and passes in front of said upper support means when said object is held in said lower support means cradle and said beam is rotated in the opposite direction.

5. The pipe lowering means set forth in claim 4 in which said beam is oscillated through an angle of not more than 90°.

6. The pipe lowering means set forth in claim 4 in which said upper and lower object support means are 30 rotatably supported on said beam.
